SPECTACLE CASE

Carl R. Jerry, St. Petersburg, Fla., assignor to Shuron Optical Company, Inc., Geneva, N. Y., a corporation of New York

Application December 2, 1953, Serial No. 395,783

2 Claims. (Cl. 206—6)

The present invention relates to spectacle cases and more particularly to sheet metal spectacle cases and to a method of covering the same. More specifically the invention relates to a method of covering the overlaying flange which cooperates with the body portion of the case to form the pocket of the spectacle case.

Heretofore it has been the practice in covering metal spectacle cases to fold the side tabs of the body portion of the covering over the overlaying flange and then to fold the front flap of the body portion of the covering over the overhanging flange and the side tabs. The front flap was made of a length to cover the side tabs, at both sides, thereby providing overlap joints at both sides of the flange. This method and construction leaves the material of the front flap, which covers the overhanging flange, exposed at both sides of the flange so that in time it becomes frayed or pulls loose. This detracts from the appearance of the case.

One object of the present invention is to provide a spectacle case covering in which the front flap will be free of wear and fraying or the possibility of pulling loose at the sides of the overhanging flange.

Another object of the invention is to provide a spectacle case cover which will have an improved appearance.

A further object of the invention is to provide a spectacle case cover which will have improved appearance and longer life.

Other objects of the invention will be apparent hereinafter from the specification and from the recital of the appended claims.

In the drawing:

Fig. 1 is a perspective view showing a metal spectacle case body placed upon a covering blank ready to have the cover applied thereto;

Fig. 2 is a fragmentary plan view on a somewhat enlarged scale showing one corner of the overhanging flange and adjacent parts of the spectacle case, and the portion of the covering that is to cover these parts;

Fig. 3 is a similar fragmentary view showing one side tab of the covering folded over the overhanging flange of the case;

Fig. 4 is a similar fragmentary view showing the front flap of the covering folded over the flange in abutting relation to the folded over tab;

Fig. 5 is a perspective view of the covered case;

Fig. 6 is a fragmentary view, similar to Fig. 4, but showing the abutting parts of the tab and of front flap dimpled to conceal the joint between them;

Fig. 7 is a fragmentary view, similar to Fig. 6, but showing the abutting portions of the tab and of the front flap dimpled and stamped to conceal the joint between them;

Fig. 8 is a perspective view, similar to Fig. 5, showing the covered spectacle case with the portions of the covering of the flange dimpled and stamped, concealing the joint between the tab and the front flap.

Referring now to the drawing by numerals of reference, 10 denotes the metal foundation portion of the

2

spectacle case. This includes the body portion 11 and a lid 12, which is hinged to the body portion at 13. The body portion is made with an overlying flange 14, lateral sides 15, and a rear side 16. The sides, together with the overlying flange 14 and base 17 of the body, provide the usual pocket for reception of a spectacle. A coil spring 18 has one end secured to the inside of the lid 10 and its other end secured to anchoring members 19 that are struck up from the body 11. This is conventional construction; and the spring 18 serves to hold the lid open or to hold it closed, after it has been moved in either direction beyond dead center position.

25 denotes the covering for the case 10. This may be made of leather, imitation leather, processed cloth, or other suitable material. Its inside surface is usually coated with glue capable of adhering to the surface of the case when heated and when pressure is applied thereto.

The lid 12 of the case is covered in conventional manner as by folding the portion 26 (shown only fragmentarily) of the covering over the edges of the lid 12 and adhering the covering to the inside of the lid after it has been heated. The present invention is not concerned with the method of covering the lid 12 of the case 10.

The portion 27 of the covering 25 for the body portion 11 of the case comprises the side flaps 28, the tab portions 29 and the front flap 30. Recesses 31 are cut in the covering material between each side flap 28 and the adjoining tab 29 to permit properly folding the covering over the sides 15 and overlying flange 14 of the case without wrinkling the cover. Recesses 32 are provided between the tabs 28 and the adjoining sides of the front flap 30 for a similar purpose.

In covering the body portion of the case, the body portion is placed on the cover portion 27, and the side flaps 28 and tabs 29 are folded over the side walls 15 and flange 14, respectively, so that the portions 28' of the side flaps cover the outsides of side walls 15 and the portions 29' of the tabs cover the corners of the flange 14, and so that the portions 28'' of the side flaps fold over the top edge and inside the side walls 15 of the case, and the portions 29'' of the adjoining tabs 29 fold inside underneath the corner of the flange 14. The dotted line 35 in Fig. 2 denotes the line of fold of the right hand side flap 28 and right hand tab 29.

When this fold has been made, the overhanging flange 14 of the pocket has been covered at each corner by a tab 29, as shown in Fig. 3. Then the front flap 30 is folded over the overlying flange 14 and underneath the same, the line of fold being denoted at 36 in Fig. 3. The inside of the lid 10 and body portion 11 of the case and the portions of the covering, which fold inside the case, may then be covered with a single piece of velvet 45 according to conventional practice.

55 The front flap 30 is generally rectangular in shape having straight edges at opposite ends; and the tabs 29 and the front flap 30 are so cut that when folded over the overhanging flange 14 they abut one another forming a butt joint as shown at 40 in Fig. 4.

60 The adjoining portions 51 and 52 of each tab 29 and of the front flap 30 are then dimpled by embossing; and a line 53 is stamped or embossed on the front flap 30 which is inclined to the edge 55 of the case at an angle to form with the adjacent side edge of the case 65 a substantially isosceles triangle whose bisector is the butt line 40, as shown in Fig. 6; or, if desired, the adjoining portions 52 and 51 may also be stamped or embossed along the line 40, to provide a heavy joining line 54 as shown in Figs. 7 and 8. Thus, the spectacle case will 70 have the appearance of having mitered corners.

The dimpling of the adjoining portions 51 and 52 of the tabs 29 and front flap 30, and the embossing of the

line 53, or of the lines 53 and 54, along these adjoining portions conceal the juncture 40, and improve materially the appearance of the covered case. Because the butt joints 40 are spaced from the side edges of the case, and the sides of the covering have no exposed edges at the side of the case, the side edges of the front flap 30 will not be subject to excessive wear, and will not fray. The covering will, therefore, maintain its appearance for the life of the covering itself.

While the invention has been described in connection with particular embodiments thereof, it is capable of other modifications, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A spectacle case comprising a body portion and a lid portion, said body portion having a bottom, opposed side walls, and a rear wall, and an overlying flange extending from the front of said body portion rearwardly, each of said side walls joining the front edge of said flange at an obtuse angle, said flange overlying the front portions of said side walls and of said bottom and constituting with the bottom and said side walls a pocket for a spectacle, and a covering for said body portion comprising a single sheet of covering material having a portion to cover the outside of said bottom, flaps at opposite sides covering the outsides of said side walls, a tab attached to each of said flaps and covering the outside portions of said flange which are laterally adjacent the side walls, and a front flap covering the remainder of the outside of said flange, the portion of said front flap, which overlies said flange, being generally rectangular in shape and of a length less than the length of said flange and having parallel, straight side edges, and each of said tabs having a straight terminal edge abutting against the adjacent straight side edge of said front flap at a point spaced from the corresponding side

4
wall to form a butt joint therewith, the said straight terminal edges of said tabs being parallel.

2. A spectacle case comprising a body portion and a lid portion, said body portion having a bottom, opposed side walls, and a rear wall, and an overlying flange extending from the front of said body portions rearwardly, each of said side walls joining the front edge of said flange at an obtuse angle, said flange overlying the front portions of said side walls and of said bottom and constituting with the bottom and said walls a pocket for a spectacle, and a covering for said body portion comprising a single sheet of covering material having a portion to cover the outside of said bottom, flaps at opposite sides covering the outsides of said side walls, a tab attached to each of said flaps and covering the outside portions of said flange which are laterally adjacent the side walls, and a front flap covering the remainder of the outside of said flange, said flap being of a length less than the length of said flange, the portion of said front flap, which overlies said flange, being generally rectangular in shape and having parallel, straight side edges, and each of said tabs having a straight terminal edge abutting against the adjacent straight side edge of said front flap to form a butt joint therewith which is spaced from the adjacent side wall, the said terminal side edges of the two tabs being parallel to form with said front flap spaced, parallel abutting joints, the portion of each tab, which overlies said flange, being approximately triangular in shape and being dimpled, and the portion of the front flap, which adjoins each tab, being dimpled over a triangular area, corresponding approximately to the dimpled area of the tab to form with the abutting portion of each tab a dimpled area of approximately isosceles triangular shape whereby to obscure said butt joint.
